UNITED STATES PATENT OFFICE.

WILLIAM A. BELL, OF KENOSHA, WISCONSIN, ASSIGNOR TO C. M. HALL LAMP COMPANY, OF KENOSHA, WISCONSIN.

DESIGN FOR A VEHICLE SIGNAL LAMP.

Application filed April 24, 1923. Serial No. 5,932. Term of patent 14 years.

To all whom it may concern:

Be it known that I, WILLIAM A. BELL, a citizen of the United States, residing in the city of Kenosha, county of Kenosha, and State of Wisconsin, have invented a new, original, and ornamental Design for a Vehicle Signal Lamp, of which the following is a specification, reference being had to the accompanying drawing, forming a part thereof.

Fig. 1 is a front elevation of a vehicle signal embodying my design, and
Fig. 2 is a side elevation of the same.

I claim:

The ornamental design for a vehicle signal lamp, substantially as shown and described.

WILLIAM A. BELL.
